CONVEYOR COUNTER

Kenneth L. Wilcox, 99 Carr St., Providence 5, R.I.
Filed June 9, 1960, Ser. No. 34,974
4 Claims. (Cl. 193—35)

This invention relates to a conveyor counter and more particularly to a form of unit counter which may be readily attached to a conveyor to automatically register the number of packages passing thereby.

It has generally been the practice to manually count the number of packages as they are delivered from a truck to a warehouse or the like and it would of course be obvious that if the number of packages is large that the manual counting becomes a tedious job. This would of course lead to errors in the counting of the packages and it is desirable to have a mechanical counter with a construction which will insure each and every package is counted as it is delivered from the truck.

It is therefore an object of this invention to provide a counting assembly which may be readily attached to a conventional construction of a conveyor which has a plurality of parallel axles supporting a number of rollers thereon.

It is another object of the invention to have a tripping means associated with the counter which will insure that a count is made no matter whether the carton is dented or is otherwise distorted from its usual rectangular shape.

It is a still further object of the invention to provide an attachment means for the counter which will insure a rigid attachment to the conveyor by attaching the counter to a portion of the conveyor which will not normally distort under usual loads.

With these and other objects in view, the invention consists of certain novel features of construction as will be more fully described and particularly pointed out in the appended claims.

In the drawings:

FIG. 1 illustrates a conveyor with a counter assembly thereon being used in the operation of discharging packages from a truck;

FIG. 2 is a top plan view of a portion of the conveyor of FIG. 1 with the counter assembly of the invention attached thereto;

FIG. 3 is an end view of the counter assembly illustrated on a larger scale with parts broken away; and

FIG. 4 is a perspective view of the counter assembly of the invention.

Referring now to the drawings, FIG. 1 illustrates a conveyor generally designated 10 which is positioned between the rear end of a truck 11 and a loading platform within a building 12. In view of the inclined position boxes such as 13 will pass down the conveyor to a loading platform within the building 12. On the conveyor there is mounted a counting assembly generally designated 14 which is located substantially midway of the length of the conveyor. The conveyor utilized is of usual construction and includes a plurality of longitudinal frame members 15 through which a plurality of axles 16 having wheels 17 are disposed. The wheels 17, of course, reduce the friction of the cartons passing down the conveyor and serve to elevate the cartons above the longitudinal supporting rails 15.

The counter assembly which is shown more particularly in FIGS. 3 and 4 comprises a supporting plate 20 with an attachment clip 21 arising from one side thereof and a second attachment clip 22 arising from the end thereof. The clip 21 may be made integral with the supporting plate 20 and bent in an upward or right angular fashion therefrom as at 23 to rise up from the

2

plate a finite distance and then is reversely bent as at 24 to provide a downwardly turned portion 25. The clip 21 therefore can generally be described as consisting of a U-shaped support means for the plate 20. The clip 22 extending at the end of the supporting plate 20 may be similarly formed from and as a continuation of the supporting plate 20 being bent upwardly substantially at right angles to the plate 20 as at 26 where it rises vertically for a distance to a reverse bend 27 where the stock is turned downwardly to extend somewhat parallel to the vertical portion and then is bent inwardly as at 28 to form a clip portion.

Referring to FIG. 2 it will be seen that the supporting clip means 21 is adapted to be received over an axle 16 and the clip support means 22 is adapted to be received over a longitudinal rail 15. This mounting means insures rigid support of the counting assembly and insures that no rotation thereof will occur. Further by virtue of the fact that a one point axle support is provided together with a longitudinal rail support, any distortion or bending of the axle or the rails will not affect the mounting of the counter upon the conveyor. It frequently happens that the axles become bent through usage and a single point mounting thereon would impede such a mounting of the counter where desired upon a conveyor. This two point mounting obviates such difficulty.

A register or standard counting mechanism 30 is secured to the supporting plate 20 in a suitable fashion such as by bolts 31 (see FIG. 3). The counting mechanism is of a conventional type and is provided with an actuating shaft 32 that extends from one end of the assembly. Attached to this actuating shaft 32 is a resilient arm 33 which is composed of resilient spring material shown in the form of a closely wound helix with a solid tip end 34 which extends within the helix a slight distance as shown better in FIG. 3. Means are provided within the counting mechanism 30 to spring bias the arm 33 into a vertical position and movement of the arm 33 from its vertical position will cause actuation of the counting mechanism to indicate passage of one package. The indication is shown at the visible indicating means shown through the window 35.

To prevent over travel of the arm 33 a stop means in the form of an upwardly bent arm 38 is provided adjacent the arm 33. This upwardly extending portion 38 from the plate 20 may have a reverse bend portion as at 39 to provide an arcuate contact for the arm 33 when it strikes the limit stop. This prevents damage of the counting mechanism 26 due to overtravel.

In operation it will be apparent that as a carton such as 13 moves down the conveyor, it will strike the actuating lever 33 moving it, thereby causing rotation of the shaft 32 and the register of a single count. After the package has passed, the arm 33 will return to a vertical position by means of the spring within the counting mechanism. Should for any reason a package 13 be damaged such that the bottom wall thereof is dented inwardly, the provision of the spring arrangement of arm 33 insures that it will extend up far enough to engage a portion of this package and cause a count since the arm 33 can be bent at substantially right angles to its normal position without damage to any of the mechanism. This thus provides a conveyor counter which eliminates the necessity of visual counting and is very reliable in operation.

The counter of this assembly may be readily attached to a conveyor whether it be damaged or not because of the two-point mounting and will stay in place regardless of vibrations.

I claim:

1. A counter for a conveyor having a plurality of longitudinal extending guide rails with a plurality of parallel axles mounted therein with rollers on said axles, a supporting plate for a counter having a clip means adapted to extend over one axle of the conveyor and having a second clip means oriented at right angles to the first clip means adapted to extend over the longitudinal rail of the conveyor, a counting mechanism affixed to the support plate, said counting mechanism having an actuating shaft extending therefrom, an actuating lever being affixed to said actuating shaft, said lever being oriented in a general vertical direction away from the supporting plate and extending above the supporting

plate a distance greater than the clip means.

2. In a counter for a conveyor as in claim 1 wherein said actuating lever is a resilient lever throughout its length.

3. In a counter for a conveyor as in claim 1 wherein there is a stop to limit the movement of said lever.

4. In a counter for a conveyor as in claim 1 wherein there is a stop to limit the movement of said lever, said stop being carried by said supporting plate.
